CLAIM

The ornamental design for a light fixture, as shown and described.

DESCRIPTION

FIG. 1 is a top perspective view of a light fixture;

FIG. 2 is a bottom perspective view thereof;

FIG. 3 is a top plan view thereof;

FIG. 4 is a bottom plan view thereof;

FIG. 5 is a front elevation view thereof; and,

FIG. 6 is a side elevation view thereof.

The broken lines depicted in FIGS. 1-6 illustrate portions of the light fixture that form no part of the claimed design.

1 Claim, 5 Drawing Sheets# US D826,450 S
